DESIGN FOR A COMBINED ASH TRAY AND HOLDER FOR CIGARETTES AND MATCHES

Clare H. Marks, New York, N. Y.

Application December 17, 1940, Serial No. 97,399

Term of patent 7 years

To all whom it may concern:

Be it known that I, Clare H. Marks, a citizen of the United States and a resident of the city of New York, borough of Manhattan, county of New York, and State of New York, have invented a new, original, and ornamental Design for a Combined Ash Tray and Holder for Cigarettes and Matches, of which the following is a specification, reference being had to the accompanying drawing, forming part thereof, in which—

Fig. 1 is a perspective view of a combined ash tray and holder for cigarettes and matches embodying my new design;

Fig. 2 is a side elevational view thereof;

Fig. 3 is a top plan view.

I claim:

The ornamental design for a combined ash tray and holder for cigarettes and matches, as shown.

CLARE H. MARKS.
